SHOE SOLING APPLIANCE

John O. Yunker, Wauwatosa, and Abraham Kahn, Milwaukee, Wis.

Application January 21, 1935, Serial No. 2,684

10 Claims. (Cl. 12—33)

The present invention relates in general to improvements in the art of manufacturing or repairing footwear, and relates more specifically to an improved appliance for facilitating attachment of the soles of shoes with the aid of adhesive, such as cement.

Generally stated, an object of the present invention is to provide an improved shoe-soling appliance which is relatively simple and compact in construction, and which is, moreover, highly effective in actual use.

It has recently become common practice, especially in the shoe repair industries, to cement the outer soles to the welts and insoles with the aid of a press having an elastic pad adapted to coact with the lower surface of the outsole, and provided with adjustable means for forcing the shoe proper into intimate contact with the upper portion of the outsole at the cement-coated surfaces. While these prior presses produce a relatively satisfactory union at the major portions of the soles and shoes, they do not, in most cases, insure proper cementing of the soles to the welts. This defect is due to the fact that the present presses do not provide for the exertion of proper downward pressure at the welts, in opposition to the elastic reaction pad, and it is impossible, with the prior practice, to produce perfect adhesion along the edge portions of the soles and welts, especially in cases where the welts have been distorted due to prolonged use of the shoes. Although it has previously been attempted to provide appliances for securing such localized pressure at the welts, these prior devices have proven unsatisfactory and uncommercial mainly because they were too complicated and difficult to manipulate, and they were not adapted to properly cooperate with shoes of various sizes and shapes.

It is therefore a more specific object of the present invention to provide an improved appliance cooperable with shoe-soling presses of the above-described general type, which will enhance the effectiveness of such presses in securing perfect unions between the shoes and soles throughout the entire contact areas.

Another specific object of the invention is to provide a welt-engaging attachment for shoe-soling presses, which is adapted to effectively cooperate with shoes of various shapes and sizes, in order to insure secure attachment of the welts to the outsoles by adhesion.

Still another specific object of the present invention is to provide a welt-engaging mechanism of relatively simple construction and which

may be readily manipulated to effectively cement a sole to the welt of a shoe.

A further specific object of the present invention is to provide an improved accessory which is cooperable with any standard shoe-soling press so as to more effectively cement the soles to the shoes, and which may be manufactured and sold at moderate cost.

These and other objects and advantages will be apparent from the following detailed description.

A clear conception of an embodiment of the invention and of the mode of constructing and of utilizing welt-engaging attachments built in accordance with the improvement may be had by referring to the drawing accompanying and forming a part of this specification, in which like reference characters designate the same or similar parts in the various views.

Fig. 1 is a full top view, showing the attachment applied to a shoe and also showing portions of a standard press cooperating with the shoe;

Fig. 2 is a side elevation of the improved appliance, showing the same cooperating with a shoe which is in engagement with an elastic pad, the latter being shown in section;

Fig. 3 is a transverse, vertical section through the assemblage of Fig. 2, taken along the line 3—3 of Fig. 2; and

Fig. 4 is an enlarged, transverse, vertical section through one side of the improved appliance.

While the invention has been illustrated and described herein as being primarily adapted for embodiment in an appliance for shoe-repairing presses, it is not intended to unnecessarily restrict the scope by such specific embodiment since some of the novel features may obviously be applicable to other types of shoe-manufacturing or repairing machinery.

Referring to the drawing, the ordinary shoe-repair press for attaching soles to the shoes by adhesion comprises in general an elastic reaction pad 6 upon which the sole 7 of a shoe 8 may be positioned during cementing of the sole to the shoe, and a vertically adjustable spindle 9 cooperable with a pressure block 10, which is, in turn, cooperable with a last 11 to urge the shoe 8 and sole 7 toward the elastic pad 6. These various elements of the shoe-repair press are relatively old and well known and are shown in greater detail in Yunker Patent No. 1,943,356, granted January 16, 1934, and in Yunker application Serial No. 680,580, filed July 15, 1933. The size and structure of the elastic pad 6 and of the block 10 and last 11 may vary in different types

of presses, and this is also true with respect to the relative location of the pressure spindle 9 and pad 6.

The improved appliance adapted to cooperate with a shoe-soling press, such as before described, includes a pair of curved sections 12 and 13 pivotally connected together at one pair of ends, as at 14, and adapted to be disposed adjacent the opposite sides of a shoe 8. To effect said pivotal connection of the ends of said sections, the end portion of one section 12 carries integrally a curved, bifurcated extension 15 into which an extension 16, carried integrally by the other section, extends. The pivot pin 14 is extended through adjacent portions of said extensions 15 and 16.

Each extension carries a hollow, cylindrical boss 17 and 18, and both sections have elongated pins 19 and 20 extended therefrom, the pin 19 entering the boss 17 and the pin 20 entering the boss 18. Openings 21 at the outer ends of said bosses permit the pins to move therethrough during pivotal movements of the sections 12 and 13 with respect to each other. In order to yieldingly repulse outward swinging movement of one section relative to the other, each pin 19 and 20 carries a confined, coiled spring 22. Said springs extend into the hollow bosses 17 and 18 and are compressed when said sections are moved pivotally outwardly.

The sections 12 and 13 are of angled form in cross section, as shown in Fig. 4. Depending from under-face portions of the horizontal flanges of the same are a plurality of U brackets 23. Each bracket has mounted therein a pivot pin 24 on which a curved welt-engaging dog 25 is mounted. Each dog 25 has an upper end flange 26 which is spaced slightly from the top portion of its bracket 23. When the dog is in normal position, as in full lines in Fig. 4. However, each dog 25 may be swung outwardly toward the vertical flange of a section, as shown in broken lines in Fig. 4, when the device is applied to a shoe. All of the dogs are arranged for independent movement, but outward movement of each dog is repulsed by a confined spring 27 having opposite ends engaging the section and an inner portion of the dog, as illustrated.

In the use of the appliance, the last 11 is positioned within the shoe to be repaired, and it is urged tightly into position by means of the pressure block 10, operated by the spindle 9. By means of spreading the sections 12 and 13 of the appliance, it may be fitted around the forward exterior portion of the shoe; and the force exerted by the springs 22 will cause said sections 12 and 13 to tightly engage said shoe portions, the position being shown in the drawing. As thus disposed, the lower, curved ends of the welt-engaging dogs 25, depended from said sections, engage in the crevices of the shoe where the outsole joins the welt and insole. The tension exerted by the springs 27 cause said dogs to exert considerable force against said shoe portions.

To hold the appliance in the proper position on a shoe, a bridging block 28 is provided. This block is positioned so as to seat on opposite portions of the sections 12 and 13 and is disposed immediately below a forward, upper extension 10' of the pressure block. Hence, when the spindle is turned so as to apply pressure on the pressure block, this pressure is applied through the bridging block 28 to the medial portions of the appliance sections 12 and 13.

From the foregoing description it will appear

that the improved shoe-soling appliance is especially suited for the repair of footwear wherein the outer soles are cemented to the welts and insoles. Difficulties heretofore inherent in the forms of presses used in the trade are entirely eliminated by the improved appliance as the sections 12 and 13 and the dogs 25 exert downward, inward pressure at the welts in opposition to the elastic reaction pad. The result is that perfect adhesion is obtained along the edge portions of the soles and welts, and this is especially important in shoes where the welts have been distorted due to prolonged use of the shoes. The improved appliance is very simple to manipulate and is readily adjustable to fit and engage shoes of varying sizes and shapes.

It should be understood that it is not desired to limit the invention to the exact details of construction herein shown and described, for various modifications within the scope of the claims may occur to persons skilled in the art.

It is claimed and desired to secure by Letters Patent:

1. A shoe-soling attachment, comprising, a member having portions adapted to be disposed adjacent the opposite sides of a shoe, a plurality of independently movable welt-engaging elements carried by said member at each of the opposite sides of the shoe, and resilient means for urging each of said elements inwardly toward the shoe, 30

2. A shoe-soling attachment, comprising, a member having relatively pivoted sections forming a U-shaped frame adapted to be disposed around the toe portion of a shoe, a plurality of independently movable welt-engaging elements 35 carried by each of said sections, and means for resiliently urging said elements inwardly toward each other.

3. A shoe-soling attachment, comprising, a member having relatively pivoted sections adapted to be disposed adjacent the opposite sides of a shoe, a plurality of independently movable welt-engaging elements carried by each of said sections, and resilient means for urging each of said elements inwardly toward the shoe. 45

4. A shoe-soling attachment, comprising, a member having relatively pivoted sections forming a U-shaped frame adapted to be disposed around the toe portion of a shoe, resilient means for urging said member sections toward each other, and a plurality of independently movable welt-engaging elements carried by each of said sections. 50

5. A shoe-soling attachment, comprising, a member having relatively pivoted sections adapted to be disposed adjacent the opposite sides of a shoe, means for urging said member sections toward each other, a plurality of independently movable welt-engaging elements carried by each of said sections, and means for resiliently urging 60 each of said elements inwardly toward the shoe. 55

6. A shoe-soling attachment, comprising, a member having relatively pivoted sections adapted to be disposed adjacent the opposite sides of a shoe, means located near the front of the shoe for swingably connecting said sections, resilient means for urging said sections toward each other, a plurality of independently movable welt-engaging elements carried by each of said members, said elements constituting a series extending 70 completely around the forward portion of the shoe, and means for resiliently urging each of said elements inwardly toward the shoe. 65

7. A shoe-soling attachment, comprising, a member having relatively pivoted sections adapt- 75

- ed to be disposed adjacent the opposite sides of a shoe, means located near the front of the shoe for swingably connecting said sections, resilient means for urging said sections toward each other, 5 a plurality of independently movable welt-engaging elements carried by each of said members, said elements constituting a series extending completely around the forward portion of the shoe, means for resiliently urging each of said 10 elements inwardly toward the shoe, and means for applying downward pressure to the medial portion of the top face of each of said sections. 15 8. A shoe-soling attachment, comprising, a member having relatively pivoted sections adapted to be disposed adjacent the opposite sides of a shoe, a plurality of independently movable welt-engaging elements carried by each of said sections, and means for applying downward pressure to the medial portion of the top face of each of said 20 sections.
9. A shoe-soling attachment, comprising, a member having relatively pivoted sections adapt-

ed to be disposed adjacent the opposite sides of a shoe, a plurality of independently movable welt-engaging elements carried by each of said sections, resilient means for urging each of said elements inwardly toward the shoe, and means for applying downward pressure to the medial portion of the top face of each of said sections. 5

10. In combination, a resilient pad engageable with the outer surface of the outsole of a shoe, means cooperating with the interior of the shoe 10 for urging the same toward said pad, a U-shaped member having sections adapted to be disposed adjacent the opposite sides of a shoe, a plurality of independently movable welt-engaging elements carried by said member, means for transmitting 15 pressure from said urging means to the medial portions of the top faces of the sections of said member, and resilient means for urging each of said elements inwardly toward the shoe. 20
